UNITED STATES PATENT OFFICE

2,598,585

CURTAIN STRETCHER AND DRIER

Leonard Miner, Bridgeport, Conn.

Application May 18, 1949, Serial No. 93,983

7 Claims. (Cl. 45—24)

1

This invention relates to curtain stretchers or dryers which have extensible frame members.

An object of the invention is to provide an improved extensible-frame curtain stretcher having few parts which are of very simple and economical construction, and having improved means providing for positive or non-slip adjustment of the frame members for length to change the size of the frame, such adjustment being easily and quickly effected.

Another object of the invention is to provide an improved curtain stretcher as set forth above, which is light in weight and at the same time strong and sturdy.

A further object of the invention is to provide an improved curtain stretcher according to the foregoing, which is simple to operate and to use.

Still another object of the invention is to provide a curtain stretcher characterized as above, which may be quickly and easily dismantled after use, and which when dismantled requires but little storage space.

In accomplishing the above objects there is provided, in accordance with the invention, a novel rectangular frame structure having extensible top, bottom and side frame members each comprising a plurality of elongate parts or bars slidably connected together, the bars being preferably made of sheet metal strips blanked and formed to telescope with each other. The lengths of the frame members, comprising the four sides of the frame, are determined by sets of elongate spacer strips which are carried respectively by the members, the strips in each set being arranged in end-to-end abutting relation. The bars constituting each frame member have stop means for engaging the ends of the set of strips carried by the member, thereby to limit shortening of the member whereby the compressed size of the frame is determined. The spacer strips have pins, preferably formed integral therewith, on which a curtain to be stretched and dried may be impaled.

Thus the size of the frame may be readily predetermined by the number of spacer strips carried by the frame members. By virtue of the abutting engagement of the spacer strips, the adjusted size of the frame is positively held, and the adjustment may be very easily accomplished without the use of tools, by merely adding or removing spacer strips as required.

The bars constituting the frame members may be quickly and economically fabricated from inexpensive sheet metal, and are so formed and shaped as to provide a rigid and sturdy structure

2

when the frame is assembled. Preferably one bar of each frame member is provided at its end with an elbow or lateral extension which constitutes a corner piece, and into which an adjacent bar slidably fits. By this organization relatively few parts are required in the construction of the curtain stretcher, the parts being simple and economical to fabricate whereby the overall cost of the stretcher is held to a low figure.

10 By virtue of the blanked and formed sheet metal construction the entire framework is light in weight and at the same time strong and sturdy for the purpose required.

15 The specific telescoping construction, together with the adjustment means comprising the spacer strips, enables the curtain stretcher to be easily and quickly set up, operated, and dismantled. By virtue of the corner or elbow construction of the bars, the frame when dismantled may be 20 stored in very little space.

Other features and advantages will hereinafter appear.

In the accompanying drawings:

25 Figure 1 is a front elevational view of the improved curtain stretcher of the invention.

Fig. 2 is a detail in section, taken on line 2—2 of Fig. 1.

Fig. 3 is a detail in section, taken on line 3—3 of Fig. 1.

30 Fig. 4 is a detail, enlarged, of a corner portion of the curtain stretcher frame.

Fig. 5 is a plan view of a spacer strip for the frame, provided with pins on which a curtain may be impaled.

35 Fig. 6 is a transverse section taken on line 6—6 of Fig. 5; and

Fig. 7 is a sectional view similar to Fig. 3, but showing a modification of the invention wherein the pin-carrying strip is disposed within the telescoping sections of the frame.

40 Referring to Fig. 1 the present improved curtain stretcher and dryer comprises a rectangular frame 10 having extensible members 11, 12, 13 and 14. The frame 10 when set up for use may

45 be carried on an easel or other suitable support; it may be disposed in an upright position as shown, wherein the frame members 12 and 14 are the sides of the frame and the members 11 and 13 the top and bottom respectively, or the

50 frame may be disposed to extend horizontally, wherein the members 12 and 13 are the side members, and the members 14 and 12 the top and bottom members respectively.

Each of the frame members 11 and 13 is formed 55 of a straight bar 15 which is telescopically re-

ceived in an elbow bar 16. Each of the members 12 and 14 is formed of a straight bar 17 which is telescopically received in an elbow bar 18. The bars 15 and 17 are similar to each other except for length; likewise, the elbow bars 16 and 18 are similar to each other except for length.

The cross sectional shape of the bars 16 is clearly shown in Fig. 3, each of said bars having a generally flat, main or body portion 19 shaped to have longitudinally extending inner shoulders 20 and curled longitudinal edges 21 which latter constitute flanges. The elbow bars 18 have a cross section similar to that of the bars 16 shown in Fig. 3.

Referring to Fig. 2, the bars 15 have generally flat or main body portions 22 formed to provide longitudinally extending inner shoulders 23 and curled longitudinal edges 24 constituting side flanges.

Each of the bars 17 has a cross section similar to that of the bar 15 shown in Fig. 2. In this figure it may be readily seen that the bars 15 are adapted to fit within, or telescope into the bars 16, and the same is true for the bars 17 and 18, a loose fit being provided whereby the frame members 11, 12, 13 and 14 may be readily extended or retracted to respectively increase or decrease their lengths.

As shown in Figs. 1 and 4 each of the bars 18 is provided at one end with an integral right-angle extension 25 whereby the end portion of the bar constitutes an elbow. The cross-sectional shape of the extension 25 is identical to the cross-sectional shape of the main portion of the bar 18, whereby the said extension may telescopically receive one end of one of the straight bars 15. The corner portion 26 of the elbow bar 18 is preferably provided with a downturned flange 27 for reinforcement purposes, the said flange also functioning as a stop in conjunction with spacer strips, as will be herein-after brought out.

The elbow bars 16 are constructed in a manner similar to the bars 18, having extensions 16a adapted to telescopically receive the straight bars 17.

For the purpose of reinforcing the frame 10 a cross member 28 is provided, comprising telescoping bars 29 and 30 having spring clips 31 at their remote ends whereby they may be removably clipped over the elbow bars 18 of the frame.

By the above telescoping construction of the frame members and cross member, the frame 10 may be readily reduced in either width or height, or increased as desired, to fit various sizes and shapes of curtains which are to be stretched and dried.

In accordance with the present invention novel means are provided for setting the lengths of the frame members 11 through 14, and thereby adjusting the size of the frame 10, and for enabling a curtain to be quickly and easily mounted on the frame.

Referring to Figs. 1, 5 and 6 this means comprises a plurality of spacer strips 32, each strip having an elongate, generally flat body portion 33 along one edge of which integral pins 34 are struck up so as to project generally at right angles to the body 33. Each spacer strip 32 is preferably provided with a pair of spring clips 35 by which it may be snapped over the bars 15, 16, 17 and 18 of the frame 10.

Referring to Figs. 1 and 4, the corner portions of the elbow bars 16 and 18 are provided with

lanced fingers 36 adapted to engage the ends of the spacer strips 32 and function as stops therefor. Thus, as shown in Fig. 1, spacer strips 32 may be clipped to the frame members in sets, each set being carried by one member and being coextensive therewith, the ends of the set engaging the stop fingers 36 whereby shortening of the frame member is prevented. By such organization the compressed size of the frame is determined by the lengths of the individual spacer strips and by the number of strips carried by the members.

When the spacer strips 32 are mounted on the members, the pins 34 project outward from the members whereby a curtain may be readily mounted on the frame by hooking it over the said pins.

A modification of the invention is shown in Fig. 7, wherein spacer strips 37 are provided having a cross sectional shape such that they may be slidably received in the telescoping bars 15, 16, 17 and 18 of the frame 10. The spacer strips 37 have laterally projecting integral pins 38 over which a curtain may be hooked. It will be understood that sets of spacer strips 37 may be carried within each of the frame members 11, 12, 13 and 14 to be coextensive therewith, the ends of the sets in this instance engaging the downturned flanges of the corner portions of the elbow bars, such as the flange 27 shown in Fig. 4. As shown in Fig. 1, a split collar 39 having a hand screw, may be disposed on the cross-brace member 30 for the purpose of limiting shortening of the same, whereby adequate bracing of the frame members 12 and 14 is provided for.

By the above construction I have provided a strong and durable and yet light-weight curtain stretcher frame which may be quickly and economically fabricated of inexpensive sheet metal, which has relatively few parts of simple and economical construction, and which may be very easily set up for use, or dismantled and stored in relatively small space. In conjunction with the frame 10, I have provided novel means for positively maintaining the frame in different adjusted sizes, said means being simple and inexpensive and easily operated by the ordinary lay person.

Variations and modifications may be made within the scope of this invention and portions of the improvements may be used without others.

I claim:

1. In a curtain stretcher frame having extensible top, bottom and side members each comprising a plurality of bars slidably connected with each other, the improvement which comprises: sets of elongate spacer strips carried respectively by the frame members, said strips in each set being in end-to-end abutting relation; means on said bars of each frame member for engaging the ends of the set carried by the member to limit shortening of said member whereby the compressed size of the frame is controlled by the lengths of the sets; and means including pins carried by said strips, on which a curtain to be stretched may be impaled.

2. In a curtain stretcher frame having extensible top, bottom and side members each comprising a plurality of recessed, open-sided bars telescopically fitting each other, the improvement which comprises: sets of elongate spacer strips coextensive with and carried respectively within the frame members, said strips in each set being arranged in end-to-end abutting relation; means

on said bars of each frame member for engaging the ends of the set carried by the member to limit shortening of said member whereby the compressed size of the frame is controlled by the lengths of the sets; and means including pins carried by said strips, on which a curtain to be stretched may be impaled.

3. In a curtain stretcher frame having extensible top, bottom and side members each comprising a plurality of bars slidably connected with each other and having corner elbows secured to said bars, the improvement which comprises: sets of elongate spacer strips carried respectively by the frame members, said strips in each set being in end-to-end abutting relation; means on said corner elbows for engaging the ends of the sets carried by the members to limit shortening of said members whereby the compressed size of the frame is controlled by the lengths of the sets; and means including pins carried by said strips, on which a curtain to be stretched may be impaled.

4. In a curtain stretcher frame having extensible top, bottom and side members each comprising a plurality of sheet-metal bars slidably connected with each other, the improvement which comprises: the bars having stamped generally flat corner elbows integral therewith, sets of elongate spacer strips carried respectively by the frame members, said strips in each set being in end-to-end abutting relation; flanges on said corner elbows, for engaging the ends of the sets carried by the members to limit shortening of said members whereby the compressed size of the frame is controlled by the lengths of the sets; and means including pins carried by said strips, on which a curtain to be stretched may be impaled.

5. In a curtain stretcher frame having extensible top, bottom and side members each comprising a plurality of sheet-metal strips having opposite flanges on their longitudinal edges, said strips sliding on and interfitting with each other, the improvement which comprises: the strips having stamped, generally flat corner elbows integral therewith; sets of elongate spacer strips carried respectively by the frame members, said spacer strips in each set being in end-to-end abutting relation; flanges on said corner elbows, for engaging the ends of the sets carried by the

members to limit shortening of said members whereby the compressed size of the frame is controlled by the lengths of the sets; and means including pins carried by said strips, on which a curtain to be stretched may be impaled.

5 6. In a curtain stretcher frame having extensible top, bottom and side members each comprising a plurality of bars slidably connected with each other, the improvement which comprises: sets of elongate sheet-metal spacer strips carried respectively by the frame members, said strips in each set being in end-to-end abutting relation; means on said bars of each frame member for engaging the ends of the set carried by the member to limit shortening of said member whereby the compressed size of the frame is controlled by the lengths of the sets; and means including pins carried by said strips, on which a curtain to be stretched may be impaled, said pins being integral with the strips and projecting from longitudinal edges thereof.

10 7. In a curtain stretcher frame having extensible top, bottom and side members each comprising a plurality of bars slidably connected with each other, the improvement which comprises: sets of elongate spacer strips carried respectively by the frame members, said strips in each set being in end-to-end abutting relation; resilient clips secured to said spacer strips, for removably 25 mounting the same on the frame members; means on said bars of each frame member for engaging the ends of the set carried by the member to limit shortening of said member whereby the compressed size of the frame is controlled by the lengths of the sets; and means including pins carried by said strips, on which a curtain to be stretched may be impaled.
